Atty.

UNITED STATES PATENT OFFICE.

JAKOB KELLER, OF ZURICH, SWITZERLAND.

MACHINE FOR GLOSSING LINEN AND THE LIKE.

1,381,471.

Specification of Letters Patent. Patented June 14, 1921.

Application filed May 20, 1920. Serial No. 382,896.

To all whom it may concern:

Be it known that I, JAKOB KELLER, a citizen of the Swiss Confederation, and residing at Zurich, Switzerland, have invented certain new and useful Improvements in Machines for Glossing Linen and the like, of which the following is a specification.

The present invention has reference to certain new and useful improvements in machines for glossing linen and the like which avoid the disadvantages of the existing machines and possess the advantage of having organs which are both movable and fixable, together with interchangeability of the glossing body or glosser, so that it can easily be set with regard to the position of the article to be glossed and rapidly interchanged according to the kind of linen after it has become cold.

20 My invention will be best understood when described in connection with the accompanying drawings, in which—

Figure 1 is a front view,

Fig. 2 a side view,

25 Fig. 3 a top view of the machine.

On the axle *a* of the device is a roller *b* covered with linen. Both ends of the axle project slightly over the roller *b* and are lodged in the U-shaped frame *c*, the hand 30 crank *d* is arranged at one end of the axle *a*. Inside the U-shaped frame *c* the ends of the band *e* are fastened, on which the board *g* is attached by means of screws *f* (Fig. 3). Two bolts *h* (Fig. 1) are passed through 35 the upper part of the frame *c* and are fastened at one end by means of a rod *i* and at the other are linked to the levers *k*. The board *g* is sloped on one side toward the roller *b*. The rod *i* is passed at both ends 40 through the frame *c* in a vertical slit *c'*. The levers *k* are pivoted in the supports *m*, which are fastened to the frame *c* and are oscillatory. In the middle of the frame *c* is a boss *o* provided with an inside thread 45 for taking up the vertical bolt *n*. A shoe *p*, provided with two notches running parallel to each other, is on the bolt *n*. The free ends of the levers *k* are lodged in these notches. The shoe *p* is maintained in elevated position by the expansion spring *q*, disposed between the support *r* carried by the bolt *n* and shoe *p*. One end of the bolt is screwed into the boss *o* lodged on the frame 50 *c*; the other end is provided with a handle *s* for easy manipulation. The glossing body or glosser *t* is secured to the rod *i*; it is

wedge-shaped and formed with two supports above with transverse bore for taking up the holding member *u*. The latter consists principally of a circular rod which is 60 bent rectangularly at one end and bears a handle *v* at the other. Between the curved part of the holding member and the handle *v* is a spring *w* attached at one end to the disk *x* lodged on the circular rod, and engaged at the other on the plate *y* which bears against the frame *c* from below. As will be seen by Fig. 2, this spring presses the plate against the frame *c*. The free end of the rectangularly curved part of the 70 holding member *u* is provided with two notches *u'* opposite each other in which the wedge *z* is inserted with its forked end so as to arrest the holding device. The wedge *z*, representing a locking member, is connected 75 with the plate *y* by a small chain *z'*.

After the glossing contrivance *t* has been —as far as this is necessary—warmed on an ironing-stove, it is placed on the rod *i* (*v*. Figs. 1 and 2), attached by engaging the 80 rectangularly curved part of the holder *u* in the transverse bores of the supports on the glosser *t* and secured by means of the locking device *z*. By pressing down the plate *y* the latter can now be brought under 85 the frame *c*, whereupon, after being freed, by the action of the spring *w*, it is pressed on the frame *c* and the glossing body is secured against oscillation around the rod. By turning the handle *s* and consequently the 90 bolt *n*, the free levers *k* whose ends are lodged in the notches of the shoe *p*, are acted on and the glossing body *t* can be raised with regard to the roller *b*, i. e. to the article to be glossed. After loosening, 95 i. e. pressing down the plate *y*, the glosser *t* can be thrust to the side of the rod *i* at will.

The levers *k*, instead of being lodged in the notches of the shoe *p*, could also be linked to the same.

100 What I claim is:

1. A glossing machine comprising a frame, a rod slidably disposed in the frame, a screw spindle on said frame, operating connection between said spindle and rod, a glossing body adjustably and detachably mounted on said rod, and frame engaging means carried by said glossing body for operative positioning thereof.

2. A glossing machine comprising a frame, 110 a rod disposed in the frame, a screw spindle on said frame, lever connection between said

spindle and rod, a glossing body mounted on said rod, a handle on said glossing body, and frame engaging means carried by said handle.

5. 3. A glossing machine comprising a frame, a rod disposed therein, a screw spindle on said frame, levers connecting said rod and spindle, a glossing body carried by said rod, a handle on said glossing body, frame engaging means on said handle, and locking mechanism on the handle.

10 4. In a glossing machine, the combination with a frame having a roller therein, of a presser rod slidably disposed in said frame 15 above the roller, rod adjusting mechanism

between said frame and rod, a glossing body adjustably and detachably mounted on said rod, and frame engaging means on said body.

5. A glossing machine comprising a frame, a presser rod therein, operating means therefor on said frame, a glossing body detachably mounted on said rod, a handle detachably carried on said body, and frame engaging means carried by the handle.

20 In testimony whereof I have affixed my 25 signature in presence of two witnesses.

JAKOB KELLER.
